223,468

COMBINED LAMP, METRONOME AND DESK SET

Robert D. Veech, 11 Yates Ave., Commack, N.Y. 11725

Filed May 1, 1970, Ser. No. 22,782

Term of patent 14 years

Int. Cl. D26—05

U.S. Cl. D48—20

FIG. 1

FIG. 2

FIG. 3

FIG. 4

FIG. 5

FIG. 6

FIG. 1 is a front elevation of a combined lamp, metronome and desk set showing my new design;

FIG. 2 is a side elevation;

FIG. 3 is a rear elevation;

FIG. 4 is a side elevation opposite to the side of FIG. 2;

FIG. 5 is a top plan view; and

FIG. 6 is a bottom plan view.

I claim:

The ornamental design for a combined lamp, metronome and desk set, substantially as shown.
